SEWING MACHINE

Bernard A. Schmitt and Allan A. Norin, Chicago,
Ill., assignors to Sears, Roebuck and Co., Chi-
cago, Ill., a corporation of New York

Application May 1, 1939, Serial No. 271,008

3 Claims. (Cl. 112—220)

This invention relates to mechanical movements, and is concerned more particularly with but is not limited to those pertaining to sewing machines.

It is an object of our invention to provide an improved drive between the motor shaft and the main shaft of a machine of the character referred to.

An additional object is to provide a drive of the character referred to exhibiting considerably reduced vibration.

It is another object to provide an improved motor speed and speed range control.

Another object is to provide an improved variable speed motor governor control.

A further object of our invention resides in the provision of a simplified and space-economizing feed dog drive enabling the motor to be attached, without crowding, on the bottom of a relatively small bed plate such as that employed on the 20 domestic type of sewing machine.

Further objects and advantages of the invention will appear as the description proceeds.

Our invention will be better understood upon reference to the following description and accompanying two sheets of drawings, in which:

Fig. 1 is a fragmentary vertical longitudinal sectional view of a sewing machine embodying features of our invention and taken as indicated by the line 1—1 in Fig. 3.

Fig. 2 is a fragmentary vertical sectional view taken as indicated by the line 2—2 in Fig. 1.

Fig. 3 is a bottom plan view taken as indicated by the line 3—3 in Fig. 1.

Fig. 4 is a fragmentary vertical cross-sectional view taken as indicated by the line 4—4 in Fig. 1.

Fig. 5 is an end elevation of the governor and control therefor appearing at the right in Fig. 3.

Fig. 6 is a bottom plan sectional view taken as indicated by the line 6—6 in Fig. 5.

Fig. 7 is an inverted plan view showing a mechanism for actuating the governor control means.

Fig. 8 is a front sectional view, taken as indicated by the line 8—8 in Fig. 7 but showing the parts uninverted.

Fig. 9 is a sectional elevation looking from the left to the right of the machine, taken as indicated by the line 9—9 in Fig. 7 but showing the parts uninverted.

Fig. 10 is similar to Fig. 7 but shows the mechanism in inoperative position.

Fig. 11 is an enlarged cross sectional view taken as indicated by the line 11—11 in Fig. 2.

Fig. 12 is a longitudinal sectional view taken as indicated by the line 12—12 in Fig. 11.

Fig. 13 is a view similar to Fig. 12 but of a modified form of resilient drive.

5 Referring now more particularly to the drawings, the bed plate 15 may be hinged to a cabinet frame 16 by suitable means (not shown) as at the side 17 thereof and preferably supports on the underside 18 thereof a motor 19 (Figs. 3 and 7), preferably driven at constant voltage from a suitable source of electricity (not shown). The motor has a shaft 20 carrying a worm 22 which drives a worm wheel 23 on a shaft 24. A second worm 26 on the shaft 24 has a 1 to 1 drive relation to a second worm wheel 27 mounted on a hook shaft 28 journaled in bearings 30.

The hook shaft supports a hook body 32 for rotation therewith. The body is provided with a loop seizing beak or hook 31 and the under thread is carried by a bobbin supported within a bobbin case 34 disposed within the hook body and maintained against rotation therewith by means of a lug 42 on the bobbin case engaged within a recess 43 in a bar 44. The bar 44 may be suitably mounted as by a pin 46 and screw 47 on the bed plate.

30 The shaft 24 extends upward through an opening 48 in the bed plate and is journaled in bearings 49 which may be eccentric for adjustment purposes. A worm 50 about the upper end of the shaft 24 and capable of relative rotation is held against longitudinal movement by thrust collars 51 and 52, the latter having a hub to engage said worm. Resilient wires 53 securely held by the collar 52 and loosely received in sockets or bores 54 in the worm 50 establish a shock-absorbing drive between the collar 52 and said worm. Said worm drives a gear 55 on a main shaft 56 in the ratio of 1 to 2. Since the drive ratio between the worm 26 and the worm wheel 27 is 1 to 1, it follows that the hook shaft 28 makes two revolutions for each revolution of the main shaft 56 and hence for each cycle of the take-up 57 and needle 58.

45 The worm 50 could, of course, be fixed to the shaft 24, although the resilient drive is preferred for the reason noted.

The head or main shaft 56 carries an eccentric 60 mounted in a pitman 61 depending from the main shaft and pivotally connected at 62 to a crank 64 fixed as at 65 to a rock shaft 66 journaled in bearings 68 and mounted on the bed plate. The rock shaft 66 preferably extends longitudinally adjacent the rear side 17 of the bed plate.

Extending from the end of the shaft 66 opposite the crank 64 is a pair of arms 70 (Figs. 1, 3 and 4) affording at their outer ends 71 bearings pivotally supporting a yoke 75. The yoke has arms 77 and 78 bridged by a bar 80.

The arm 77 may be formed with a channel 82 to slidably and adjustably receive a lug 83 formed on a feed dog 84, said lug preferably having a slot 86 through which a screw 87 passes to securely maintain the dog in the desired position of adjustment.

The eccentricity of the eccentric 60 is such as to impart oscillatory movement to the crank 64, thus causing the shaft 66 to rock, and, by means of the yoke 75, impart essentially horizontal reciprocatory movement to the feed dog 84.

Also disposed about the main shaft 56 is an eccentric 90 mounted in a pitman 91 pivoted at 92 to a crank 93 fixed as at 94 (Fig. 3) to a second rock shaft 96, suitably journaled in bearings 97, said shaft 96 running alongside the rock shaft 66. The shaft 96 extends to a point adjacent the yoke 75 and carries a crank 100 preferably fixed thereto as at 101. A link 103 is pivoted as at 104 to the crank 100 and as at 105 to the yoke 75.

The eccentricity of the eccentric 90 is such that as the main shaft 56 rotates, the crank 93 oscillates, rocking the shaft 96 and, through the crank 100, link 103 and yoke 75, imparting an essentially vertical reciprocation to the feed dog 84.

It is thus apparent that the eccentric 60 imparts a generally horizontal reciprocation of the feed dog and the eccentric 90 imparts a generally vertical reciprocation to the feed dog. Thus the feed dog is influenced simultaneously by the eccentrics 60 and 90 and the path of its motion simulates a flat oval, the dog completing one cycle for each revolution of the main shaft 56.

As is clear from the foregoing, the hook shaft 28 rotates twice for every revolution of the main shaft 56 and cycle of the feed dog. The uniformity as well as the rate of rotation of the hook shaft is determined by the uniformity and rate of rotation of the motor shaft 20. Of each two revolutions of the hook shaft 28, one is a working revolution and the second is an idling revolution. The continuous rotation of the hook shaft 28 is very desirable since a substantial amount of vibration inherent in other constructions wherein the hook shaft has interrupted rotation is avoided. Also, by virtue of the relationship of the shafts, cranks and associated parts, only a relatively short throw of the up-and-down feed is necessary, resulting in correspondingly reduced eccentric movement and vibration. All of the linkage at the bed plate is disposed on one side 110, leaving ample space on the other side 111 for the mounting of the motor on the lower side of the bed plate without crowding.

A governor 115 is mounted to rotate with the motor shaft 20 and carries a motor circuit closing means 116 comprising contacts 117 and 118 mounted on arms 119 and 120 connected by springs 121 and 122 respectively to brackets 123. Pivotally connected at 124 to the base 125 of the governor 115 is a bell crank lever 126 having an arm 127 to which is pivotally connected as at 128 a link 129 having a lug 130 engaged with the arm 120. The other arm 135 of the lever 126 may have a button 136 engageable with an end 138 of an arm 140 of a lever 141 pivoted at 142 to a bracket suitably mounted on the bed plate or other relatively stationary part. The lever 141

has another arm 143, and either of its arms may be pressed by a spring 145 in a direction to cause the arm 140 to move the bell crank lever arm 135 away from the observer viewing Fig. 5, thereby urging the contact arm 120 away from the other contact arm 119 and thus normally separating the contacts 117 and 118 and holding the motor circuit open.

It is evident that upon movement of the lever 141 against the action of the spring 145, i. e., toward the observer viewing Fig. 5, the spring 122 will be free to move the contact 118 into engagement with the contact 117, so as to close the motor circuit and thereby operate the motor 19. The contacts 117 and 118 are movable radially away from the axis of the motor shaft 20 in response to centrifugal force, which force, as to the contact 117, is opposed by the spring 121 and, as to the contact 118, is opposed by the spring 125. It is evident that by altering the position of the lever arm 143, the position of the contact 118 and hence the motor speed at which the circuit will open is correspondingly controlled.

In accordance with our invention there is provided a governor control actuating mechanism within convenient access of the operator. Although various actuating mechanisms may be provided and adapted to be operated by foot, hand or otherwise, we prefer to provide such a mechanism which is under the control of a knee, as, for example, the right knee of the operator. To this end, we have provided a mechanism such as that appearing in Figs. 7 to 10. Said mechanism may comprise a lever 150 having a fixed pivot 151. To one end of the lever 150 a link 153 is pivoted as at 154, the link 153 being guided between the frame or cabinet 16 and an offset bracket 157 secured to the underside of the frame as at 158. The link 153 has at its free end a hook 160 providing a notch 161 into and out of which the curved end 163 of the lever arm 143 readily slips as the bed plate 15 is swung down into and up out of operative position. A link 165 is pivoted at 166 to the link 153 and at 167 to a lever 169 pivoted at 170 to the lever 150. The free end 172 of the lever 169 is received in a slot 173 in a manipulating lever 175 pivoted at 176 to a bell crank lever 177 pivoted at 180 to the frame 16. On the side of the pivot 180 opposite the pivot 176 the lever 177 is movably pivoted at 182 to a link 183 which is in turn pivoted at 184 to the end of the lever 150 opposite the pivot 154.

The lever 175 preferably has a rounded free end bearing portion 186 projecting so that its convex side extends adjacent the right side of the right knee of the operator, and also within easy reach of the right hand of the operator. As will be clear upon reference to Figs. 7 and 8, by moving the knee to the right and thus moving the lever end 186 to the right, as shown by the arrow 187 (Fig. 7), the bell crank lever 177 is swung about the fixed pivot 180 in a direction to draw the link 183 leftward, thereby actuating the lever 150 and link 153 in such manner as to swing the end 163 of the lever 141 to the right, i. e., toward the observer viewing Fig. 5, against the action of the spring 145, thereby permitting the spring 122 to move the contact 118 into engagement with the contact 117 so as to close the motor circuit and start the motor 19. As the motor speeds up, the contact 117 moves outward by centrifugal action. Since the outermost position of the contact 118 is controlled by the lever 141 which is in turn controlled by the operator

through the lever 175, it follows that the operator determines and can vary within the ultimate limits of the device the speed at which the motor runs, the governor serving to hold the motor to any selected speed. When the knee pressure on the lever end 186 is withdrawn, the spring 145 acts upon the lever 141 and, through such lever, upon the control linkage therefor to return the various parts to the positions shown in Fig. 5.

It is advisable but not absolutely necessary to withdraw the hook 160 to some such position as that shown in Fig. 10 when the bed plate is to be raised or lowered. In the previous operation of the control linkage for the lever 141, the link 165 and lever 169 play no part. For the purpose of moving the hook 160 out of and into the position shown in Fig. 7, the link 165 and lever 169 are utilized. For this purpose the operator grasps the lever end 186 in her hand and swings it rearward about the pivot 176, as shown by the arrow 188, thereby swinging the lever 169 forward about the pivot 170, and thus, through the link 165, swinging the hook 160 forward as shown by the arrow 190. By a reverse swinging of the lever end 186, the hook 160 may be restored to the position shown in Fig. 7.

When the parts are arranged as shown in Fig. 10, and the bed plate is in operative position, it is evident that the motor cannot be accidentally started.

It is clear from the foregoing that we have provided a simple, compact, neat, substantially noiseless drive from the motor to the main shaft and hook shaft, whereby the latter rotates without hesitation and hence without vibration twice per revolution of the main shaft, and a similarly advantageous feed dog drive from the main shaft, including shafting disposed at one side of the hook shaft, leaving ample space for the motor without crowding and thus requiring a substantially smaller bed plate than has heretofore been necessary for a machine of comparable size. Also we have provided an efficient motor speed control at all times under the control of the operator and which enables the operator to run the motor at any desired speed, the control being adapted to be rendered inoperative whereby to preclude accidental operation of the motor when it is plugged in for electricity.

Of course the wires could be fixed in the worm 58 and loose in the collar 52 if desired.

Another form of shock-absorbing drive is shown in Fig. 13. This arrangement includes the shaft 24, an upper collar 200 fixed at 201 to the shaft, a worm 202 longitudinally slidable on the shaft and keyed as at 204 thereto so as to rotate therewith, a lower collar 205 suitably fixed to the shaft as at 206, and a coil or other suitable spring or other resilient member 208 between the worm and the collar 205, constantly urging the worm against the collar 200. When excessive resistance is offered to the drive, the rotation of the shaft 24 is not interrupted, but, instead, the worm wheel 58 exerts a reactive camming force on the worm 202, camming the latter downward along the shaft notwithstanding the resistance of the

spring 208. The worm preferably has an extension 209 projecting within the upper end of the spring, the extension 210 on the lower collar 205 serving as a stop to limit downward movement of the worm and fitting in the lower end of the spring, whereby to retain the spring in proper position. The collars 200 and 205 are preferably molded of phenolic condensation product or other suitable preferably non-metallic material so that the engagements between the worm and the collars will be noiseless or substantially so.

Various modifications may suggest themselves to those skilled in the art without departing from the spirit of our invention, and, hence, we do not wish to be restricted to the specific form shown or uses mentioned, except to the extent indicated in the appended claims, which are to be interpreted as broadly as the state of the art will permit.

We claim:

1. In a device of the class described including a frame, a sewing machine carried thereby and including a swingably mounted bed plate, and a motor for said machine; a motor control carried by said bed plate and comprising a member movable to vary the speed of the motor, means comprising an element mounted at the underside of said frame and movable in one direction by a knee of the operator seated at the machine for moving said member, and means operative in response to a different movement of said element for rendering said member non-responsive to knee operation.

2. In a device of the class described including a sewing machine, a motor therefor, and a motor control comprising a member movable to vary the speed of the motor; an arm connectible with and disconnectible from said member, means operatively connected with said arm and arranged to be moved by a knee of an operator seated at the machine to move said member when said arm is connected to said member, said means being operative to disconnect said arm from said member so as to render said member non-responsive to knee action, whereby accidental operation of said member by the knee is obviated.

3. In a device of the class described including a sewing machine, a motor therefor, and a motor control comprising a member movable to vary the speed of the motor; an arm connectible with and disconnectible from said member, means operatively connected with said arm and arranged to be moved by a knee of an operator seated at the machine to move said member when said arm is connected to said member, said means being operative to disconnect said arm from said member so as to render said member non-responsive to knee action, whereby accidental operation of said member by the knee is obviated, said arm being mounted to actuate said member only when the knee is moved sidewise, said arm being movable to disconnected position in response to a manual pull by the operator upon said means.

BERNARD A. SCHMITT.
ALLAN A. NORIN.
